UNITED STATES PATENT OFFICE.

CYRUS F. BILHIMER, OF IRWIN, PENNSYLVANIA, ASSIGNOR OF TWO-THIRDS
TO S. D. LAUFFER AND WILLIAM WILLIAMS, OF SAME PLACE.

PERMUTATION-LOCK.

SPECIFICATION forming part of Letters Patent No. 415,492, dated November 19, 1889.

Application filed June 5, 1889. Serial No. 313,147. (Model.)

To all whom it may concern:

Be it known that I, CYRUS F. BILHIMER, a resident of Irwin, in the county of Westmoreland and State of Pennsylvania, have invented 5 a new and useful Improvement in Permutation-Locks; and I do hereby declare the following to be a full, clear, and exact description thereof.

My invention relates to locks, and more especially to a combination or permutation lock, which is suitable to be employed on doors of private dwellings, offices, safes, vaults, &c., its object being to provide a permutation-lock which is simple in construction, 15 yet which may be changed to a number of combinations and can only be opened by a person knowing the same, while also doing away with the necessity of a key.

To these ends my invention consists in certain improvements and combination of parts, all of which will be more fully hereinafter set forth.

To enable others skilled in the art to make and use my invention, I will describe the same 25 more fully, referring to the accompanying drawings, in which—

Figure 1 is a plan view of the interior of the casing. Fig. 2 is a cross-section showing the tumblers in position. Fig. 3 is a perspective view of the top of one of the tumblers; Fig. 4, a perspective view of the bottom of same; Fig. 5, a view of bottom of actuating-tumbler. Fig. 6 is a plan view of the lock, showing the combination closed, the back 35 plate of the casing being removed. Fig. 7 is a like view showing combination open. Fig. 8 is a cross-section showing the cams secured to the central spindle. Figs. 9 and 10 are perspective views of the cams. Fig. 11 is a 40 view of the locking-dog. Fig. 12 is a perspective view of the dog employed to lock the bolt from the inside, and Fig. 13 is a view of the pawl for locking the actuating-tumbler.

Like letters of reference indicate like parts 45 in each of the figures of the drawings.

In the drawings, *a* represents the circular casing constructed of any suitable material and adapted to receive the several parts of the device which compose the lock and the 50 parts necessary to operate the locking appa-

ratus. This casing *a* is to be secured by means of screws to the inside of the door, and consists in the large seat *a'* and the flanged portion *a''*, surrounding said seat. In the center of the seat *a'* of the casing *a* is the central opening 55 *a''*, through which the central spindle by which the lock is operated from within or without passes. Surrounding this opening *a''*, within the seat *a'* of the casing, is the boss *b*, a portion of said boss being cut away, as at *b'*, this 60 portion being on the lower side of the boss when the lock is secured in position on the door. Directly above the boss *b*, on the inner face of the casing, is formed the wedge-shaped lug *c*. Within the seat *a'* of the casing the 65 tumblers *d* are arranged. These tumblers, as shown in Figs. 3 and 4, are constructed of cast-iron or other suitable material, and are provided with the flanges *d'*, said flanges being perforated at regular intervals to form 70 the holes *d''*, into any one of which may be inserted the pins *d'''*. A large opening *d''* is formed in the center of the tumblers *d*, and extending in from said openings are the notches *d''''*. 75

The upper face of the tumblers *d* have formed thereon the lugs *d''''*, which lugs are arranged to be directly opposite the notches *d''''* on the upper side of the tumblers, while small nicks *d'''''* are cut in the outer edge of the 80 tumblers in line with the center of the lug *d''''*.

When the tumblers *d* are arranged in position within the seat *a'* of the casing, they rest one upon the other, as shown in Fig. 2, the flange of one tumbler resting upon the 85 upper face of the next lower, and so on to the bottom one, which rests against the casing itself. In this position they are arranged to be turned or actuated by the actuating-tumbler *e*, which is similar in construction to the 90 tumblers *d*, with the exception of the toothed periphery *e'*, and as the said actuating-tumbler is the top one of the series there is no necessity of a lug corresponding to the lug *d''''*. The actuating-tumbler *e* has on its 95 flange *e''* the small nick *e''''*, which corresponds in position to the nicks *d'''''*, and a pin *e'''*, corresponding to the pins *d'''*.

In order to get at the tumblers *d* and *e* to change the combination when the casing is 100

secured to the door, I furnish the casing *a* with an opening *a*⁴ of sufficient size to allow the several pins in the different tumblers to be removed and inserted in different holes, 5 according as it may be desired to change the combination. This opening *a*⁴ has a removable cover *a*⁵, which may be screwed or otherwise suitably secured to the casing. The central spindle *f* is constructed in two sections, 10 and is commonly known as a "swiveled spindle," the one section *f*' screwing into the section *f*², so that one section may be turned independently of the other. This central spindle *f* passes through the central opening *a*³ of the casing and the openings *d*⁴ of the tumblers, and on its ends are to be secured the knobs or handles for operating the lock.

The cams *h* and *i* (shown in Figs. 9 and 10) are adapted to be fitted on the central 15 spindle *f*—one on each section—and as the said spindle is square in section the cams *h* and *i* are furnished with square bearings to fit on said spindle. The cam *h* is provided with a recess *h*' on one side, and on the other 20 side is cut away to form the shoulder *h*². A wing *h*³ extends up from one side of the recess *h*', and an annular seat *h*⁴ is formed within the cam. The cam *i*, which is adapted to fit on the section *f*² of the spindle *f*, has on 25 one end the neck *i*', which, when the cams are fitted on the spindle, enters into the annular seat *h*³ of the cam *h* and turns easily therein. This cam *i* is also provided with the recess *i*². In securing the cams *h* and *i* 30 upon the swiveled spindle *f* the cam *h* is first slipped on said spindle over the section *f*² and onto the section *f*' to a point just beyond the point of connection of the two sections *f*' *f*², where it is prevented from any further 35 movement on the section *f*' by the pin *f*³, passing through said section and against which it abuts. The cam *i* is then slipped upon the section *f*² of the spindle *f* until the neck *i*' enters the annular seat *h*³ of the cam 40 *h*, and as the point of connection of the sections *f*' *f*² is within this annular seat *h*³, when the section *f*² is turned the cam *i* will turn with it, the neck *i*' turning freely in the annular seat *h*³. In this way the section *f*² and 45 the cam *i* thereon have a movement entirely independent of the section *f*'.

When the cams *h* and *i* have been fitted on the spindle *f* in the manner described, the tumblers having been arranged within the 50 casing in the proper manner, the said cams are inserted in the casing and fit within the space formed in the center of the casing by the openings *d*⁴ of the tumblers. The section *f*² of the spindle passes through the central 55 opening *a*³ of the casing, while the neck *i*' on the cam *i* enters the said opening *a*³, and the shoulder *i*² rests upon the boss *b*.

When the lock is secured to the door, the cam *h* is arranged to have the recess *h*' face 60 the lower side of the casing and the shoulder *h*² face the top of said casing, while the cam *i* is arranged to have its recess *i*² face the top

of the casing. The latch-bar *k* has the pin or stud *k*', which enters into the recess *i*² of the cam *i*, so that when the cam is turned 70 the stud *k*' moves with it, and so draws the latch-bar in the same direction, and when the cam *h* is turned to the right the shoulder *h*² will engage with the stud *k*' and move it in the same direction. 75

A dog *l* (shown in Fig. 11) has at one end the locking-arm *l*' and at the other the circular lug *l*², said lug being adapted to fit in a seat *m* in the casing, while the locking-arm *l*' enters the recess *h*' in the cam *h* and passes 80 down to the bottom of the casing to that portion of the boss which is cut away for this purpose. When the combination is closed, this locking-dog *l* prevents the cam *h* from being turned in either direction; but when 85 it is open—that is, when all the notches *d*⁵ of the tumblers *d*, as well as the one on the actuating-tumbler *e*, are at the same point and coincide with each other, as in Fig. 7—the locking-dog *l* will drop of its own accord, 90 and so allow the cam *h* to be turned. A suitable seat *n* in the casing *a* has journaled therein the gear-pinion *o*, and adapted to be operated from without by a suitable spindle *o*' and handle connected thereto. The cogs 95 of the pinion *o* mesh with the toothed periphery *e*' of the actuating-tumbler *e*, so that by turning the pinion *o* the actuating-tumbler *e* is operated, and with it all the other tumblers, as will be hereinafter more specifically shown. 100

In order to lock the actuating-tumbler *e*, when it is desired to prevent any one from meddling with the lock and changing the combination, a pawl *p* is arranged to slide to 105 and fro in a suitable guideway *q*, formed in the flanged portion *a*² of the casing, the said pawl extending through an opening *q*' in the casing to a point without said casing, where it can be forced in to engage with 110 the toothed periphery of the actuating-tumbler *e*, or withdrawn therefrom, as it may be desired, to lock or unlock the said actuating-tumbler *e*. The pawl *p* has formed thereon the lug *p*², and around said lug is 115 the coiled spring *r*, which fits within the seat *r*', surrounding the guideway *q*. Upon this coiled spring *r* rests the dog *s*, the said spring entering a circular seat *s*' in said dog, so that the dog may be moved to and fro in a 120 small radius, working on the spring *r* and the lug *p*² as a pivotal point, the object of the spring *r* being to force up the dog *s*, so that the end *s*² of the dog which extends without the casing through the same opening 125 *q*' as the pawl *p* will not interfere with the working of said pawl. As the arm *s*³ of the dog *s* moves in a small radius on the pivotal spring *r*, it may be operated from without the casing and so moved as to come in contact with the shoulder *k*² on the latch-bar *k*, 130 which will prevent the latch-bar from being moved either way from within or without, so producing what is commonly known as a

"dead-latch." A coiled spring t , held in position by a suitable lug t' in the casing a^2 , has an arm t^2 , which is forced against a suitable abutment k^3 on the latch-bar k , so that when the lock has been opened and the hand has been removed from the knob or handle the latch-bar will fly back again in position to lock the door, which movement will be produced by the said spring t .

Having now described the several parts which go to make up my improved lock, I will describe its operation when secured to the door, and the manner of operating the combination.

As above stated, the casing a is secured to the inside of the door and the central spindle f passes through said casing and the door to a point without where a suitable knob or handle is secured to said spindle, a similar knob or handle being also secured to the inner end of said spindle, and the spindle operating the tumblers also passing through the door. After securing the lock to the door, the tumblers are arranged according to the combination desired, and in describing the operation of the lock I will take a simple combination in order to give a clear explanation of the same.

For convenience in description, I will designate the tumblers d by the numerals 1, 2, and 3, beginning with the top one as they are shown in Fig. 2. The pin d^3 is inserted in the hole d^2 in the flange d' of the tumbler d , the hole selected in this case being the one to the right of and next to the nick d^7 on the edge of the tumbler. The tumbler 3 is then placed in the bottom of the casing and turned until the pin d^3 comes in contact with the wedge-shaped lug c , which presents a flat face for the said pin d^3 to rest against and holds it firmly in position. The pin d^3 is then inserted in like manner in the corresponding hole in the tumbler 2, which is placed upon the tumbler 3 and turned until the pin d^3 comes in contact with the lug d^6 on the tumbler 3. Again the pin d^3 is inserted in the corresponding hole in the tumbler 1, which also rests upon the tumbler 2, and the said pin is brought in contact with the lug d^6 on the tumbler 2. When the tumblers 1, 2, and 3 have been thus arranged, the notches d^5 in said tumblers will all coincide with each other and be in the same position. Upon the tumblers 1, 2, and 3, arranged as described, is placed the actuating-tumbler e , with the pin e^3 inserted in the third hole to the right of the nick e^2 on its flange. By turning the pinion o the actuating-tumbler e is also turned and, together with it, the tumblers 1, 2, and 3 in their order, for when the actuating-tumbler e is turned until its pin e^3 comes in contact with the lug d^6 of tumbler 1 said tumbler will be carried around with the actuating-tumbler e until the pin d^3 of tumbler 1 comes in contact with the lug on tumbler 2, which in turn will be carried around until its pin comes in contact with the lug on

tumbler 3, when all the tumblers will turn until the pin on tumbler 3 comes in contact with the wedge-shaped lug c , which brings all the tumblers to a full stop. If the pins have been inserted in the holes, as described above, it will be found that by turning the pinion o to the right until all the tumblers, including the actuating-tumbler, come to a full stop, the notches d^5 will all coincide with each other; but as the pin e^3 of the actuating-tumbler was not placed in the hole corresponding to the holes into which the pins d^3 of tumblers 1, 2, and 3 were inserted, it will be found that the notch e^4 of the actuating-tumbler does not fall in the same position or coincide with the notches d^5 of the other tumblers, but is some distance beyond. In order to bring, therefore, all the notches into coincidence, so that the locking-dog l will drop into said notches and allow the latch-bar k to be operated, it is necessary to turn the actuating-tumbler back to the point where the notch e^4 will coincide with the notches d^5 . In order, therefore, to discover how many turns must be given to the handle secured to the spindle o' , to which the pinion o is secured, which operates the actuating-tumbler e to bring said actuating-tumbler back to the point where its notch e^4 will coincide with the notches d^5 , the cover a^5 on the opening a^4 of the casing a is removed and the pinion o is turned to the left until the nick e^2 on the flange of the actuating-tumbler is in line with the nicks d^7 on the tumblers 1, 2, and 3, and as these nicks are formed in line with the notches d^5 it is readily apparent that when all the nicks are in a line with each other all the notches will likewise coincide, and the arm l' of the dog l will be free to drop from the recess h' of the cam h into said notches and allow the latch-bar k to be operated from the outside. The number of turns which it required to bring the nick e^2 into line with the nicks d^7 is accurately observed, when the cover a^5 is again secured in place on the opening a^4 , and the lock can only be opened by the person having knowledge of the number of turns requisite to be given to the spindle o' to bring all the notches into coincidence. When the notches have all been brought to coincide with each other, the dog l will fall into the position shown in Fig. 7, the arm l' dropping into said notches. The knob or handle on the end of the spindle f on the outside of the door may now be turned, so that the shoulder h^2 is brought into contact with the stud k' on the latch-bar k , and carries said stud, together with the latch-bar k , in the same direction, the ends of said latch-bar moving in suitable guides in the casing. The door can then be opened and the spring t forces the latch-bar back to its former position when the hand is removed from the knob. The combination is again closed by giving the pinion o two or three turns, which causes the actuating-tumbler e to force the arm l' back into the recess h' of the cam h . As stated before, on account of the swiveled spindle f the

latch-bar can always be operated by the knob on the inside of the door; but when it is desired to prevent this and form a dead-latch, the end s^3 of the dog s which extends without the casing is turned to throw the arm s^3 back of the shoulder k^2 on the latch-bar, so that the latch-bar k cannot be moved in either direction, while at the same time the pawl p is forced into engagement with the teeth of the actuating-tumbler and so prevents the said actuating-tumbler from being turned.

It is readily apparent that the combination may be changed to many different combinations by simply removing the cover a^5 from the opening a^4 and altering the position of the pins passing through the several tumblers, and then by turning the pinion o observe the number of turns necessary to bring the notches into coincidence with each other when the cover a^5 is again secured in place.

By means of the construction above described I am enabled to produce a permutation-lock which is simple in construction and one which is well adapted for use in private dwellings, offices, safes, or vaults where a secure lock is required.

What I claim as my invention, and desire to secure by Letters Patent, is—

1. In a permutation-lock, the combination, with the casing, of the tumblers arranged one upon the other, a swiveled spindle passing through said casing and tumblers, cams mounted on said spindle one on each section, the cam on one section having a recess adapted to receive a stud on the latch-bar and to move said latch-bar when the section carrying the said cam is turned, the cam on the other section having a recess adapted to receive an arm of a locking-dog which prevents the said section of the spindle from being turned together with the cam, substantially as and for the purposes set forth.

2. In a permutation-lock, the combination, with the casing, of the tumblers d , the actuating-tumbler e , and the opening a^4 in said casing, by which the combination may be changed, substantially as and for the purposes set forth.

3. In a permutation-lock, the combination, with the casing, of the wedge-shaped lug c , the tumblers d , said tumblers having the flange d' , holes d^2 therein, pins d^3 , adapted to engage with lugs d^6 , nicks d^7 , notches d^8 , substantially as and for the purposes set forth.

4. In a permutation-lock, the combination, with the casing, of the tumblers d , arranged one upon the other and adapted to be turned by the actuating-tumbler e , said actuating-tum-

bler consisting of the flange e^4 , holes e^5 , pin e^3 , nick e^2 , toothed periphery e' , and meshing with a pinion o , by which said actuating-tumbler is turned, substantially as and for the purposes set forth.

5. In a permutation-lock, the combination, with the casing a , of the central opening a^3 , the swiveled spindle f , composed of the two sections $f' f^2$, passing through said central opening, the cams $h i$, mounted on said spindle within the casing a , the cam h , mounted on the section f' and having the recess h' , the shoulder h^2 , and the annular seat h^3 therein, adapted to receive the neck i' of the cam i , mounted on the section f^2 of the spindle f , said cam having also a recess i^2 , substantially as and for the purposes set forth.

6. In a permutation-lock, the combination, with the casing a , of the spindle f , composed of the sections $f' f^2$, the cams $h i$, mounted on said sections, recesses $h' h^2$ on said cams, the one recess h' of the cam h adapted to receive the arm l' of the locking-dog l pivoted to the casing a , a shoulder h^2 , adapted to come in contact with the stud k' of the latch-bar k when the section f' is turned, and the other recess i^2 of the cam i adapted to receive and move the stud k' of the latch-bar k when the section f^2 is turned, substantially as and for the purposes set forth.

7. In a permutation-lock, the combination, with the casing a , of the tumblers d , the actuating-tumbler e , having the toothed periphery e' , the pinion o , the pawl p , sliding in the guideway q and extending without the casing through opening q' , said pawl being arranged to enter and be withdrawn from the toothed periphery e' , substantially as and for the purposes set forth.

8. In a permutation-lock, the combination, with the casing a , of the swiveled spindle f , the cams $h i$, mounted thereon, the stud k' , latch-bar k , shoulder k^2 on said latch-bar, the pawl p , lug p^2 thereon, coiled spring r , dog s , having seat s' , in which coiled spring r enters, the end s^2 , extending without the casing a through opening q' , so that by moving the end s^2 the arm s^3 may be swung around to come in contact with the shoulder k^2 of the latch-bar k , and so form a dead-latch, substantially as and for the purposes set forth.

In testimony whereof I, the said CYRUS F. BILHIMER, have hereunto set my hand.

CYRUS F. BILHIMER.
